US0D1015069S

(12) **United States Design Patent** (10) Patent No.: **US D1,015,069 S**
(45) Date of Patent: ** Feb. 20, 2024

(54) **DRINKING BOTTLE**

(71) Applicant: **KFS Marketing, Inc.**, Schulenburg, TX (US)

(72) Inventor: **Elgin R. Kristinik**, Schulenburg, TX (US)

(73) Assignee: **KFS Marketing, Inc.**, Schulenburg, TX (US)

(**) Term: **15 Years**

(21) Appl. No.: **29/816,788**

(22) Filed: **Nov. 24, 2021**

(51) LOC (14) Cl. **09-01**

(52) U.S. Cl.

USPC **D7/509**; D7/532

(57) **CLAIM**

The ornamental design for a drinking bottle, as shown and described.

DESCRIPTION

FIG. 1 is a top perspective view of a drinking bottle showing my new design;

FIG. 2 is a bottom perspective view thereof;

FIG. 3 is a side view thereof;

FIG. 4 is a top view thereof; and,

FIG. 5 is a bottom view thereof.

The broken lines in the drawings depict environmental subject matter only and form no part of the claimed design.

1 Claim, 4 Drawing Sheets
